SAFETY DEVICE FOR THE PREVENTION OF
OVERLOADING CRANES AND THE LIKELillie B. Neal and Blanche M. Stoner, Bremerton,
Wash., assignors to J. O. Neal, Port Orchard,
Wash.

Application December 23, 1930, Serial No. 504,384

6 Claims. (Cl. 177—311)

Our invention relates to safety devices for the prevention of overloading of locomotive and other cranes, and it consists in the constructions, arrangements and combinations herein described 5 and claimed.

It is an object of our invention to provide a safety device for cranes and the like wherein an operator of the crane may be apprised of the load upon the crane, thus avoiding accidents due 10 to an overloading of the crane, which in many instances causes overturning thereof.

It is a further object of the invention to provide a safety device in which a visual indicator is employed, operable in conjunction with an 15 audible signal.

A still further object of the invention is the provision of a safety device wherein a warning of load limit will be given at any danger point of the radial swing of the boom.

Additional objects, advantages and features of 20 invention will be apparent from the following description and accompanying drawings forming a part of this application, wherein,

Figure 1 is a side elevation of a locomotive 25 crane equipped with one safety device,

Figure 2 is a top plan view of the boom,

Figure 3 is a plan view of the indicator,

Figure 4 is a vertical section of the indicator and illustrating the electrical circuit for the 30 audible signal,

Figure 5 is an enlarged vertical section on the line 5—5 of Fig. 3, illustrating the operating mechanism for the indicator, and

Figure 6 is a detail of one of the drums.

It will be understood that we do not limit ourselves to the adaptation of our device to locomotive cranes, but, for illustration, we have shown the invention as applied to a locomotive crane 10, which may be of any usual construction embodying a boom 11. The boom 11 is suitably mounted for vertical swinging movement as at 12, and movable radially with the cabin 13, as is customary.

The crane 10 embodies a power drum 14 having 45 a load line 15 threaded through a sheave 16 mounted at the outermost point of the boom 11 and through block 17 from whence the cable is passed around a sheave 18. From this sheave, the cable 15 is extended rearwardly and trained 50 about a pulley 19 carried upon a lever 20 mounted adjacent the base of the boom 11, as clearly shown in Fig. 2. After passing through the pulley 19, the cable is extended forwardly for passage around a pulley 21, mounted upon the forward 55 end of the boom 11, but to the rear of the sheaves

16 and 18. The cable 15 is finally secured to the block 17 as at 22. It is evident that the particular arrangement of the cable 15 from the power drum 14 to its dead end, as above described and shown, have no relation to this invention and that that portion between the pulley 19 and the shackle 22 may be considered the dead end of the cable. The stress on the cable 15 is, of course, the same at all points therein and depends on the weight lifted and the number of cable-sections supporting the block 17. In the drawings this stress is therefore one-third of the weight being lifted, but if the dead end were loosed from the block 17 and attached directly to the lever 20, the stress therein would be one-half that of the 15 weight, while if it passed twice around the pulleys in the block 17 and the end of the boom and thence to the lever 20, the stress therein would be one-quarter that of the weight.

From a consideration of Fig. 2, it will be noted 20 that the lever 20 is pivotally mounted upon one side of the boom 11, as indicated at 23, and adjacent the opposite end is suitably apertured for mounting of a compression spring 24. The spring is confined within a suitable housing which is 25 secured by a turn-buckle or other suitable adjusting device 25 to the base of the crane 10. The tension of the spring may thus be varied by adjustment through the turn-buckle.

The lever 20 may be apertured as at 26 in order 30 to vary the attachment of the pulley 19, as found necessary, thereby varying the proportion of the stress, in the weight-raising cable 15, which is counterbalanced by the spring 24 and therefore varying the extent of movement of the lever 20 35 for a given load on the crane boom.

A cable 27 is attached to the lever 20 adjacent its free end and passes therefrom under the pulley 28', adjacent the pivot pin 12 of the boom, and thence around suitable pulleys 28 to our indicator 29, which will be fully described herein-after. A cable 30 extends from our indicator, suitably guided by pulleys 31 and is attached to the boom 11 as at 32. We preferably include adjusting means 33 in the cables 27 and 30 to take 40 up any slack which may occur through stretching, or otherwise.

From the foregoing, it will be apparent that as the weight is applied to the power line 15, a pull will be exerted upon the cable 27; and that 50 any raising movement of the boom 11 will cause a corresponding slackening movement to the cable 30 and vice versa.

Our indicator 29 is mounted within the cabin 13 in a position immediately before an operator 55

of the crane, and in our present construction embodies a housing 34 having a shaft 35 journalled in the upper part thereof. A cam or drum 36 is keyed upon the shaft 35 and is preferably eccentrically mounted with respect to the shaft, so that any variation in the travel of the boom 11 may be readily accommodated. The drum 36 is suitably grooved to receive the cable 27, the end of which is secured therein.

10 A drum 37 is also keyed upon the shaft 35, and has a cable 38 coiled therearound to the lower end of which there is secured a counterweight 39, adapted to keep the cable 27 taut.

15 As clearly shown in Fig. 5, a hollow shaft 40 is revolvably mounted on the shaft 35 and has keyed thereon drums 41 and 42. The shaft 40 projects through the housing 34 at one side but stops short of the projecting end 35a of the shaft 35. Indicator hands 43 and 44 are secured upon the 20 projecting ends of respective shafts 35 and 40 for rotary movement about the dials 45 and 46, respectively, caused by rotation of respective drums 38 and 42.

25 Secured to the drum 41, we provide a cable 47, to the lower end of which there is attached a counterweight 48 adapted to keep the cable 38 taut.

30 The counterweights 39 and 48 are movable longitudinally of the housing 34, and are suitably guided in their paths by a guide-way 49.

35 The cable 38 is coiled about the drum 42 and the end thereof secured to the drum in a suitable manner.

40 It will be apparent that a pull upon either of the cables 27 or 38 will cause rotation of its associated drum, and consequent movement of the indicator hands 43 or 44, as the case may be. It is also apparent, since an increase in the weight lifted causes a tension in the cable 27 and a 45 counterclockwise rotation of the shaft 35 and its indicator hand 43, and a raising of the counterweight 39, and an increase in the leverage of the weight or the distance that the boom end extends from the cabin 13 causes a slackening of the cable 38 and consequently a clockwise rotation of the shaft 40 and its indicator hand 44, and a lowering of the counterweight 48, that the hands 43 and 44 turn in opposite directions on an increase of either the weight or its leverage, and 50 that the counterweights 39 and 48 also travel in opposite directions on such increase. When the crane is inactive and the boom is raised, the counterweight 48 is at the top of its travel and the counterweight 39 is at its lowest point of 55 travel. When the combined effect of an increase in the weight and/or leverage is such as to endanger the safety of the crane, the said counterweights will have moved to the relative positions shown in Fig. 4, though it must be understood that this condition may occur at any point in the travel of the weights, for instance, an extremely heavy weight will cause the counterweights 39 and 48 to meet at the upper end of their travel, thus indicating that the boom must be held substantially vertically when handling such a load, while a comparatively light load will cause them to meet at the lower end of travel when the boom is extended as low as possible. The crane can be safely handled so long as the counterweight 70 48 is higher than the weight 39, but any increment of added weight or leverage will immediately bring them into line.

75 To provide an audible signal, we mount a pair of contracts 50 and 51 upon the counterweights 39 and 48. These contacts are suitably insulated

and of a length to afford a brushing contact one with the other, during movement of the counterweights. An electric bell 52, and battery 53 is in electrical connection with the contacts 50 and 51 so that the bell will be sounded upon completion 5 of the circuit through movement of the counterweight.

The operation of our device is substantially as follows:

We will say that we are about to elevate an 10 object twenty feet away from the center of gravity of the crane, and the load limit at this radius is 10 tons. The movement of the boom 11 to position to bring the block 17 to a point centrally of the object to be elevated will cause a move- 15 ment of the cable 38, and in doing so rotation of the drum 42 is effected, with consequent move- 20 ment of the indicator hand 44 on the dial 46 to indicate the movement of the boom. During movement of the drum 42, a like movement is im- 25 parted to the drum 41, which in turn moves the counterweight 48 to a predetermined point. Now, if the object to be lifted does not exceed the permissible 10 tons the crane may be operated, as usual through the power drum 14. Also the pull 30 exerted through the power line 15 will pull the lever 20 compressing the spring 24, and pulling the cable 27. The pull upon the cable 27 causes rotation of the drum 36 and rotation of the hand 43 to indicate the weight being lifted. How- 35 ever, should the weight exceed the assumed 10 tons, the hand 43 will turn until it assumes a position directly over the hand 44. The move- 40 ment of the hand 43 has also brought the counter- 45 weight 39 directly opposite the counterweight 48, and therefore the contacts are in contact- 50 ing relation one with the other, consequently sounding the bell 52, to indicate an excessive load and return of the boom to the vertical.

Upon release of a load, the hands 43 and 44 55 will assume their normal zero reading, brought back to such position through the counterweights 39 and 48. It should also be noted that the hands 43 and 44 are synchronized with the contacts 50—51 carried by the counterweights. 50

From the foregoing it will be apparent that we have provided a safety device which is simple in construction and efficient in operation, and one which may be readily installed upon cranes 55 already in use.

56 What is claimed is:

1. A safety device for cranes comprising a swinging boom; a weight-raising cable therefor; an indicator having a pair of concentric dials; a pair of indicator hands mounted in the axis of said 60 dials and adapted to indicate, respectively, the radius of said boom and the weight being raised by said cable; a shaft for each of said hands; cable means connected between said boom and one of said shafts; means mounted on said boom 65 and connected to said weight-raising cable and movable thereby in response to the load applied thereto; cable means connected between said other shaft and said load-responsive means; and counterweights operably connected with said last 70 two cables whereby said cables are maintained taut.

2. A safety device for cranes comprising a vertically swinging boom; a weight-raising cable 75 therefor; an indicator having a pair of concentric dials; a pair of indicator hands mounted in the axis of said dials and adapted to indicate, respectively, the radius of said boom and the weight being raised by said cable; a shaft for each of said hands, cable means connected be- 80

- 5 between said boom and one of said shafts; means mounted on said boom and connected to said weight-raising cable and movable thereby in response to the load applied thereto; cable means 5 connected between said other shaft and said load-responsive means; counterweights operably connected with said last two cables whereby said cables are maintained taut; and electric contacts mounted on said counterweights and adapted 10 to move therewith and to come into electric contact with each other and in circuit with an electric signal whereby said signal will be energized upon mutual contacting of said contacts during movement of said counterweights.
- 15 3. A safety device for cranes or the like, comprising a vertically swinging boom; a lever pivoted at one end to said boom and extending transversely thereof; a weight-raising line, wholly independent in its operation of the operation of said 20 vertically swinging boom, and having its dead end connected with said lever and having the weight-raising force applied to its other end; a counter-balancing spring between said lever and said boom; an indicator; a pair of rotatable hands; 25 and cable means between the respective hands and said lever and boom, whereby said hands are rotated in opposite directions to indicate respectively an increase in the radius of said boom and the weight applied to said weight-raising line.
- 30 4. A safety device for cranes having a means for raising a weight at variable radii from the center of gravity of the crane, and independent means for changing the said radius; an indicator; a pair of concentric shafts mounted therein and each 35 carrying an indicator hand; a pair of operating drums mounted on said concentric shafts; cables wound on both said drums and operatively connected respectively to the weight-raising means and to the radius-changing means, whereby an 40 increase in both said means will cause the corresponding drums to rotate in opposite directions; a second pair of drums mounted on said concentric shafts; cables wound on said second pair of drums in directions opposite to the directions of 45 the cables wound on the first pair of drums on the same shafts, respectively; and counterweights on said second pair of cables.
5. A safety device for cranes having a means for raising a weight at variable radii from the center of gravity of the crane, and independent means for changing the said radius; an indicator; a pair of concentric shafts mounted therein and each carrying an indicator hand; a pair of operating drums mounted on said concentric shafts; cables wound on both said drums and operatively connected respectively to the weight-raising means and to the radius-changing means, whereby an increase in both said means will cause the corresponding drums to rotate in opposite directions; a pair of counterweights; and connecting means between said counterweights and said concentric shafts whereby said counterweights tend 10 to oppose the motion of the respective shafts under the action of said weight-raising means and said radius-changing means.
- 15 6. A safety device for cranes having a means for raising a weight at variable radii from the center of gravity of the crane, and independent means for changing the said radius; an indicator; a pair of concentric shafts mounted therein and each carrying an indicator hand; a pair of operating drums mounted on said concentric shafts; 20 cables wound on both said drums and operatively connected respectively to the weight-raising means and to the radius-changing means, whereby an increase in both said means will cause the corresponding drums to rotate in opposite directions; a pair of counterweights; connecting means between said counterweights and said concentric shafts whereby said counterweights tend 25 to oppose the motion of the respective shafts under the action of said weight-raising means and said radius-changing means; an electric signal circuit; and a pair of electric contacts mounted in the signal circuit and operatively attached to the respective counterweights and adapted to move therewith into contact with each other to close 30 the signal circuit when the combined action of the weight lifted and the radius of action thereof exceeds a predetermined amount.

LILLIE B. NEAL.
